Primary Examiner — Lauren R Calve(74) *Attorney, Agent, or Firm* — Gulick Law; Karima Gulick(57) **CLAIM**

The ornamental design for a closet organizer, as shown and described.

DESCRIPTION

FIG. 1 is a front perspective view of a closet organizer;

FIG. 2 is a front view thereof;

FIG. 3 is a rear view thereof;

FIG. 4 is a side view thereof;

FIG. 5 is an opposite side view thereof;

FIG. 6 is a top plan view thereof; and,

FIG. 7 is a bottom plan view thereof.

The broken lines in the figures are included for the purpose of illustrating environmental structure and form no part of the claimed design.
